DOOR OPERATING MECHANISM

James E. Bancroft, Detroit, Mich., assignor, by
mesne assignments, to The Peelle Company,
Brooklyn, N. Y., a corporation of New York

Application January 23, 1933, Serial No. 653,199

5 Claims. (Cl. 268—49)

The invention relates to door operating mechanisms and has more particular reference to operating mechanisms for doors of passenger elevators and of that type operated by individual electric motors.

In the present state of the art one type of operating mechanism which has been used consists of a lever mechanism connected to the doors and actuated by a crank which when turned through one-half revolution will open the doors and upon reversal of the same will close them. This imparts a substantially harmonic movement to the doors, but it is essential that the movement of the crank should be limited to one-half revolution, as anything more or less than this would result in leaving the doors either partly open or partly closed. The crank is actuated from an electric motor through the medium of a step-down transmission and the inertia of the parts will continue the movement after the motor is de-energized. Therefore to stop the crank near its dead center, it is necessary either to de-energize the motor in advance of the completion of movement of the crank or to apply a brake to the mechanism for quickly arresting movement. A brake mechanism is objectionable as it requires frequent service to keep it in proper adjustment and also complicates and increases the cost of the apparatus and generates objectionable noise. On the other hand, the de-energizing of the motor in advance of the completion of the crank movement slows the operation and it is difficult to attain uniformity of action in successive operations.

It is the primary object of the present invention to provide a means for accurately stopping the motor and mechanism driven thereby, so as to insure the complete closing or opening of the door at each operation. It is a further object to accomplish this result in a mechanism which is operated at relatively high speed. Still further it is an object to obtain the result with an exceedingly simple and inexpensive construction avoiding the use of mechanical brakes or other complications.

Another defect in door operating mechanisms of the type above referred to is that in case of failure in the power operation it is difficult or impossible for the operator within the cage to open the door. It is therefore another object of the invention to obtain a construction with which the door can always be manually opened by the operator within the cage and without disconnecting the power operating means or rendering the same inoperative for further power

operations. To attain the various objects as above, the invention consists in the novel construction as hereinafter set forth.

In the drawings:

Fig. 1 is a front elevation showing my improved operator as applied to a pair of oppositely opening doors;

Fig. 2 is a similar view showing its application to two-speed doors;

Fig. 3 is a diagram illustrating the electrical connections;

Figs. 4, 5 and 6 are views showing the manual operation of the door.

In the operation of electric elevators it is quite usual to employ induction motors of the poly-phase type and similar type small individual motors for operating the doors. With my improvement I use the same type of individual door actuating motors, viz., induction motors, but have combined therewith a novel means for overcoming the inertia of the moving parts. This permits of operating the mechanism at relatively high speed and at the same time insuring the complete closing or opening of the door. The means employed for thus arresting movement of the motor and associated mechanism is the passing of direct current through one or more of the field coils, which has the effect of producing an electro-magnetic brake quickly bringing the mechanism to a stand-still. In some installations D. C. current is available, but if it is not, it can be easily obtained through the use of a rectifier.

As illustrated in Fig. 1, A is an electric motor of the induction type which is directly connected to a step-down transmission gearing such as worm gearing B for operating a crank arm C. This crank arm is connected to a lever mechanism for operating the doors, which as shown comprises the link connecting rod D and a bell crank lever E, one arm E' of which is slidably connected to a bearing F on the door G. The proportion of the parts is such that one-half rotation of the crank C will move the door from closed position shown in full lines to the open position indicated in dotted lines. There is also a connection including an arm E² of the bell crank lever, a connecting rod H and a lever I for operating the complementary door G' in the opposite direction.

The electric circuits for controlling the operation of the motor are shown diagrammatically in Fig. 3 in which 1, 2 and 3 are the three leads of a three-phase electric service. These leads extend to an electro-magnetically operated reversing switch 4 which is manually controlled by the operator through the push buttons or other cir-

circuit closers 5 and 6. The push button 5 closes an electric circuit including the conductor 7 from the lead 2 and the solenoid 8 for operating the three-pole switch 9 for connecting the conductors 1^a, 2^a, 3^a with the conductors 1^b, 2^b, 3^b leading to the motor A. The push button 6 closes a branch circuit through the conductor 7^a including the solenoid 8^a for operating the three-pole switch 9^a for effecting a reversing connection with the motor. Thus as shown the operation of this switch 9^a will connect the lead 1 with the conductor 1^a, the lead 2 with the conductor 3^b and the lead 3 with the conductor 2^b.

To de-energize the motor after each operation, circuit breakers are placed in the electric circuits 1 and 7^a and are operated by the rotation of the crank C as it nears the completion of its half revolution. As shown, a circuit breaker 16 is placed in the circuit 1 and is operated by a cam J on the crank shaft C'. In the same manner a circuit breaker 11 is placed in the circuit 7^a and is actuated by a cam J' on the crank shaft C'. The cams J and J' are substantially diametrically opposite each other on the shaft C', the first de-energizing the motor at the end of the door opening movement and the latter de-energizing the motor at the completion of the door closing movement.

As thus far described, there would be nothing to check the inertia of the motor and connected parts after the opening of the motor circuits and therefore as above described I provide an electromagnetic brake which operates as follows: 12 and 13 are D. C. leads and as shown in Fig. 3 the current is derived from the polyphase current 30 through the operation of a rectifier 14 which receives current from the leads 2 and 3. The lead 12 extends to contacts 15 and 16 respectively in the switches 9 and 9^a and the lead 13 extends to contacts 17 and 18 in said switches. There are, 35 however, circuit breakers 19 and 20 arranged in the conductor 13 and respectively controlled by solenoids 21 and 22 in the circuits 7 and 7^a arranged in parallel with the solenoids 8 and 8^a. These circuit closers 19 and 20 are provided with 40 dash pots 23 or other means which will delay the opening thereof after their respective solenoids 21 and 22 are de-energized.

In the operation of the parts as thus far described, the pressing of the push button 5 will 50 simultaneously energize the solenoids 8 and 21, the former moving the switch 9 so that three movable contact arms 24, 25 and 26 close with the contacts 27, 28 and 29 and connect the conductors 1, 2 and 3 respectively with the conductors 1^b, 2^b and 3^b. This energizes the motor A and continues the rotation of the same until the cam J operates the circuit breaker 19 in the circuit 1, thereby de-energizing the solenoids 8 and 21. The solenoid 21 when energized closes 55 the circuit closer 19 and after said solenoid is de-energized the circuit closer 19 remains closed for an interval on account of the retarding of movement by the dash pot 23. This gives time for the contact arms 25 and 26 to move away from the contacts 28 and 29 and close with the contacts 15 and 17. As the latter are supplied 60 with direct current from the leads 12 and 13, and as the circuit closer 19 still remains closed, direct current is supplied through the conductors 2^b and 70 3^b to the motor A and will energize the electromagnetic brake for stopping rotation. However, the direct current is only passed through the motor for the brief interval during which the circuit closer 19 remains closed. The operation 75 effected by the pressing of the push button 6 is

similar to closing the electric circuit 7^a and operates the switch 9^a to drive the motor A in reverse direction. This continues until the cam J' operating the circuit breaker 11 de-energizes the motor and direct current is then supplied thereto during the interval in which the circuit closer 20 remains closed. To avoid the necessity of holding the push buttons 5 and 6 down during the operation, circuit closers 20 operated by the switches 9 and 9^a will respectively close shunts 10 around the buttons 5 and 6.

As the lever mechanism for opening and closing the doors is driven by the crank C which is arrested at or near its dead center, and as the transmission B is a worm gear, this would constitute an irreversible mechanism preventing the manual operation of the doors. I have therefore devised a construction of mechanism arranged intermediate the crank and the door which permits of manual operation and without rendering the mechanism inoperative for subsequent automatic operation. This as shown in Fig. 1 comprises a triangular frame having its sides pivotally connected at the several angles and two of the sides E' and E³ constituting the bell crank lever before referred to. The third side E⁴ is formed with a break joint E⁵ therein and an extension E⁶ of this side forms an operating handle. Thus when the operator draws downward upon the handle E⁶ it will break the joint E⁵ and collapse the triangle permitting the side E³ which is attached to the connecting rod D to remain stationary while the side E' which is attached to the door is moved in a direction to open the door as indicated in dotted lines. After such manual operation the door may if desired be manually closed, but if it is not, then an operation of the motor A such as would normally open the door, will restore the lever parts to normal position so that the following operation of the motor 40 to close the door will be effective.

Fig. 2 shows a modified construction of mechanism for operating a telescopic door in which one door leaf K is actuated by a sliding connection with the end of the lever L while another door leaf K' is actuated by a link L' connected centrally to the leaf L so as to move said leaf one-half the distance of the leaf K. Otherwise the construction of the mechanism is substantially as previously described.

Figs. 4, 5 and 6 illustrate a door operating mechanism similar to that shown in Fig. 1 respectively in closed position, in half open position and full open position, effected by manual operation.

What I claim as my invention is:

1. In a door operator the combination with power actuated irreversible lever mechanism for opening and closing the door, of a triangular frame forming a bell crank lever and a connecting element in said lever mechanism, the sides of said frame being pivotally attached to each other and normally in rigid relation, and one of said sides having a break joint therein, and manually operable means for opening said door adapted in its initial operation to break said joint and to permit the collapsing of said triangular frame.

2. In a door operator the combination with power actuated irreversible lever mechanism for opening and closing the door, of a triangular frame forming a bell crank lever and a connecting element in said lever mechanism, said frame having its sides pivotally attached to each other, one of the sides being connected to the power,

another side to the load and the third side having a break joint therein, and manually operable means for breaking the joint in said third side to collapse said frame and to open the door without actuation of said power means.

3. In a door operator the combination with power actuated irreversible lever mechanism for opening and closing the door, of a triangular frame forming a bell crank lever and an element 10 of said lever mechanism, said frame having its sides pivotally attached to each other, one of said sides being connected with the power, another side connected with the load, and a third side having a break joint therein, and a lever forming an extension of said third side adapted to break said joint when said mechanism is in position for closing the door and to move said load side relative to said power side to open the door.
4. In a door operator, the combination of a reversible electric motor, a step-down transmission mechanism, a crank operated thereby, means for energizing said motor to alternately operate the same in reverse directions, means

for de-energizing said motor when said crank has moved through slightly less than one-half revolution, and a lever mechanism actuated by said crank to open or close the door including a triangular frame forming a bell crank lever, the sides of said frame being pivotally attached to each other and normally in rigid relation, one of said sides having a break joint therein and means manually operable when said motor is stationary for breaking said joint and collapsing 10 said triangular frame to thereby open said door.

5. In a door operator, the combination with a power actuated irreversible mechanism, of a lever mechanism actuated thereby for opening and closing the door including a triangular frame 15 forming a bell crank lever, the sides of said frame being pivotally attached to each other and normally in rigid relation, one of said sides having a break joint therein, and means manually operable when said irreversible mechanism is 20 stationary for breaking said joint and collapsing said triangular frame to thereby open the door.

JAMES E. BANCROFT.
